United States Patent Office

Des. 194,571
Patented Feb. 12, 1963

194,571

BOAT

Clifton M. Mercer, 4408D Westside Drive, Dallas, Tex.

Filed Sept. 13, 1960, Ser. No. 62,128

Term of patent 14 years

(Cl. D71—1)

FIG. I is a top plan view of a boat showing my new design;

FIG. II is a sectional view taken along the line II—II of FIG. I;

FIG. III is a bottom plan view thereof.

The dominant features of the design reside in the portions shown in full lines.

I claim:

The ornamental design for a boat, substantially as shown and described.
